UNITED STATES PATENT OFFICE.

FRED A. DENNETT, OF SHEBOYGAN, WISCONSIN.

DESIGN FOR A VENEER-PRESSING MEMBER.

SPECIFICATION forming part of Design No. 34,945, dated August 13, 1901.

Application filed March 28, 1901. Serial No. 53,372. Term of patent 14 years.

To all whom it may concern:

Be it known that I, FRED A. DENNETT, a citizen of the United States of America, residing at Sheboygan, in the county of Sheboygan and State of Wisconsin, have invented and produced a certain new, useful, and original Design for an Article of Manufacture—to wit, a Veneer-Pressing Member—of which the following is a specification, reference being had to the accompanying drawings, forming a part hereof.

In said drawings, Figure 1 is a plan view of a veneer-pressing member embodying my design. Fig. 2 is a longitudinal sectional view taken on line 2 2 in Fig. 1. Figs. 3 and 4 are cross-sectional views taken on lines 3 3 and 4 4 in Fig. 2. These four views are deemed necessary for full illustration.

The leading and essential feature of my design for a veneer-pressing member consists of the peculiar and novel formation of the upper surface of the same.

The portion of the upper surface of my design bounded by an imaginary straight line joining the points *d d* and the lines *d g*, *g h*, and *h d* is rectangular and its surface, aside from a depressed portion hereinafter referred to, is in one plane. The depressed portion starting from an indefinite substantially straight line joining points *a a* is edge-outlined as follows: The sides start from the points *a a* and

proceed backward on substantially straight lines substantially parallel with the sides *d g* and *d h* to points *b b* and from the points *b b* around on a semicircular line touching a point *c*. The slopes of the depressed portion are gradual and shaped substantially as shown in Figs. 2, 3, and 4.

The front portion or edge of my design starting from the imaginary straight line joining points *d d* proceeds forward and down on irregularly-curved surfaces straight across from side to side to a line joining points *e e*. The front portion bounded by lines *f i*, *f e*, *i e*, and *e e* is rectangular, and its plane is parallel with the upper flat surface.

The several minor features of my design may be stated as follows: The bottom is flat, and its plane is parallel with the planes of the flat portion of the upper surface. The sides are parallel planes and stand at right angles to the bottom, as do the ends.

Having thus described my design, what I claim is—

The design for a veneer-pressing member, substantially as shown and described.

Signed by me this 28th day of February, A. D. 1901.

FRED A. DENNETT.
